UNITED STATES PATENT OFFICE.

MAURICE C. GARLICK, OF EASTON, PENNSYLVANIA.

SWITCH AND THE LIKE.

Application filed August 22, 1923. Serial No. 658,696.

To all whom it may concern:

Be it known that I, MAURICE C. GARLICK, a citizen of the United States, and a resident of Easton, county of Northampton, 5 and State of Pennsylvania, have invented a certain new and useful Improvement in Switches and the like, of which the following is a specification.

My invention relates to the construction 10 of railway switches, mates, frogs and the like.

According to one feature of my invention, the supporting part of the switch, mate, frog, or the like structure and the wearing 15 portions thereof are made separately, and the wearing portion is made removable from the supporting portion.

According to another feature of the invention, provision is made for automatically 20 supporting the heel of the switch tongue in properly elevated position, notwithstanding the wear to which same is subjected in use.

All the parts of apparatus in accordance 25 with my invention are preferably so constructed that they may be installed, renewed or removed with a minimum of labor and trouble. This feature is of great utility in enabling necessary installations and changes 30 to be made readily and substantially without interruption to traffic. Other objects of the invention will appear in connection with the following description of an embodiment of the invention illustrated and described to afford an understanding of the invention, 35 but not imposing limitations thereon.

In the drawings Fig. 1 is a plan view of a switch. Fig. 2 is a part sectional and side view of the switch shown in Fig. 1. Fig. 40 3 is a side view showing the general relation of the switch supporting structure to the road bed. Fig. 4 is a cross-section on line 4—4, Fig. 1. Fig. 5 is a section on line 5—5, Fig. 1. Fig. 6 is a section on line 45 6—6, Fig. 1. Fig. 7 is a cross-section on line 7—7, Fig. 1. Fig. 8 is an isometrical view of the switch supporting member. Fig. 9 is a perspective of the removable switch wearing member, and Fig. 10 is a perspective 50 of the switch tongue.

The switch supporting member or housing 10 is constructed to form a permanent part of the track installation and is supported on suitable supports, such as cross-ties 11. It

preferably is constructed as a steel casting 55 comprising side walls 12, 12 and integral cross-webs 13, 13, which preferably extend downward flush with the bottom 14 of member 10, but do not extend upwardly as far as the side walls 12, 12, leaving open spaces 60 between them and leaving a recess 15 above them and between the upper parts of sidewalls 12, 12, in which recess the removable wearing switch or mate member 16 is received and supported. The side wall members 12, 12 and recess 15 are of such form 65 as to receive the removable wearing members provided. In the form shown recess 15 is widened out at its end 15^a where the heel of the switch is located and narrowed 70 at the end 15^b, where the point end of the switch is located.

The removable wearing member 16 is constructed separately, preferably as a casting 75 and of a material, such as high manganese steel, having a tough body with a surface which is hardened by the pounding to which it is subjected in wear. Such removable wearing member 16 is of any suitable construction and may be a frog, mate or the 80 like, or may comprise switch rails 17, 18, pivot member 19 for the switch tongue and the switch tongue 20. The rails 17, 18 are preferably formed integral with the bottom web or floor plate 21, which is of a form 85 adapted to be received in the recess 15 of the housing 10, and to be supported upon the cross webs 13.

Means are provided for locking the wearing part member 16 in the housing or supporting member 10, and in the form shown wedging keys 22 are provided for this purpose. These keys, which are widened at the bottom at 22^a, and provided at said widened portions 22^a with extending portions 90 comprising inclined upper walls 23 and 24, are inserted in slots 25 cut in the side of member 16, or in the wall members 12, or part in each, which slots 25 have wedging extensions 26 connected therewith 95 into which wedges or keys 22 may be driven by any suitable instrument by driving them longitudinally of the housing, and may be withdrawn by driving them out in the reverse direction until they reenter slots 25, 100 and whereupon the member 16 is freed and can be removed. One wedge on each side of member 16 is illustrated for simplicity 105

of showing, but as many slots and wedges may be provided as may be needed, and other forms of connecting or keying means may be used.

It will be seen that with the construction so far described, the housing or supporting portion of the switch, mate or frog may be cheaply constructed of inexpensive material and permanently installed, while the more expensive part subjected to greatest wear is made separately and inserted and keyed in place. This results in great saving in construction cost, and the inserted parts when worn can be removed and replaced in a few moments and at relatively small expense. Furthermore, ample clearance space is provided therebelow in the housing 10 so that drainage is quick and complete and the switch can not readily freeze up, and if the space under member 16 should become clogged after some time, the removable part 16 can be removed upon loosening and pulling out a few wedges and the space below it cleaned out and the member 16 removed with the greatest simplicity and readiness. The web or floor plate member 21 connecting rail members 17 and 18 has an extensive and ample seating on webs 13 throughout its width and length, and being wedged downwardly upon its supports is firmly and securely held and supported. While I have shown the two part construction above referred to, particularly in connection with switches, it is to be understood that same is applicable to mates, crossovers, frogs and other intersecting track sections where extremely heavy wear is encountered.

The tongue 20 is supported on the floor plate 21, and for the most part such support is sufficient even after considerable wear.

At the heel or pivot part 20^a of tongue 20, where wear on tongue 20 is concentrated and greatest, as soon as any looseness or give is caused by wheels running onto the heel of the switch tongue, such looseness and wear is cumulative, and the switch construction is speedily subjected to heavy hammering and pounding strains, and even to breakage, if this condition is permitted to continue.

According to one feature of my invention provision is made for automatically compensating for wear at this point as fast as same occurs, thereby avoiding the dangerous and troublesome condition above referred to.

In the construction shown such automatic compensation is secured as follows. The integral floor plate 21 of member 16 is stepped down at 29 under the heel 20^a of switch tongue 20, and this stepped down part 29 extends below the fixed pivot member 19, being narrowed to substantially a point at the innermost portion as indicated at 30. The heel 20^a of tongue 20 terminates at the top

thereof in a concave arcuate margin 31, which is adapted to fit against the coacting convex arcuate margin 32 of stationary pivot member 19. The under part of heel portion 20^a of tongue 20 is provided with downwardly and rearwardly extending portions 33, 34 respectively, the former of which extends down to the stepped down portion 29 of wearing member floor 21, and the latter of which is pointed at 35. The pointed part 35 fits in the similarly shaped recess 36, thus permitting the tongue 20 to turn pivotally about the point 35, which is at substantially the center of the curves 31, 32. The under surface 37 of the downward extension 33 is preferably formed on a slight incline and may be provided with a series of small steps 37^a or the like arranged on an incline. The heel 20^a of tongue 20 is supported by such under surface 37 resting on a wedge block 38, which preferably has a series of flat steps 39 arranged on an incline which is the reverse of inclined under surface 37, the wedge block 38 being supported on the stepped down portion 29 forming an integral part of the removable wear member 16.

The extension 34 of tongue 20, taking under the stationary pivot member 19, provides a stop against upward movement of the heel of tongue 20, as is clearly shown in Fig. 6.

Means are provided for forcing the wedging block 38 into wedging engagement with the under surface 37 of the heel of tongue 20. In the form shown, spring means are utilized for this purpose, and same is located in a box 40 on the outside of one of the walls 12 of housing member 10. An opening 41 is provided for enabling communication between box 40 and the space within housing 10, and is so arranged as to make the various parts readily accessible for assembly and removal of parts.

A lever 42 extends through this opening 41 and has a hooked inner end 42^a adapted to be engaged with one or another of the plurality of notches 43 provided in the downward extension 21^a of floor 21, thereby providing for adjustability of lever 42. Lever 42 bears against the thicker end of wedge block 38, which preferably has a notch or recess 38^a for keeping lever 42 in proper relation thereto, as shown in Figs. 1 and 6, and is provided at its outer end within the box 40 with spring means for holding it against block 38, so as to secure wedging engagement between wedge block 38 and the under surface 37 of the heel 20^a of tongue 20.

This spring and its supports are so constructed and arranged as to be readily assembled and readily removable and so that any desired tension can be put on the spring.

A pull spring 44 is used for the reason that it is practically self-cleaning or self-

freeing, and in case of freezing or clogging it is not put out of action as a compression spring may be. One end 45 of spring 44 is hooked over the hook shaped end 46 of lever 42. The opposite end 47 is connected to a yoke 48 provided with a plurality of notches 49. In the form shown, a cross-bar 50 having a hook form twist 51 at its middle is engaged by such hook 51 with the end 47 of spring 44, and the ends of such cross-bar 50 are inserted in any one of the several pairs of notches 49 in yoke 48. A pair of lugs 53 are formed on the inner sides of box 40 and are adapted to be engaged by slots or recesses 54 in the yoke 48 so as to form a pivotal support for said yoke. Such pivotal support being higher than lever 42, and the stop bar 54 for yoke 48 being also located fairly low in the box and below the pivotal support at 53 for yoke 48, it will be seen that in tensioning or stretching the spring 44 by depressing the yoke 48 until it strikes stop member 54, the yoke 48 passes the dead center and holds the spring in its expanded state. Box 40 is supplied with a removable cover 55 fitting in groove 56 and preferably flush with the top of housing 10.

It will be seen that the parts described effectively prevent excessive depression and wear of the heel part of the switch tongue and that they can be assembled and disassembled practically without tools in the most expeditious way. The yoke 48 being lifted, the cross-bar, spring and yoke may all be lifted out and the lever 42 and wedge block 38 removed through the side hole 41, and reversely the wedge block may be put in place, the lever 42 hooked in one of the notches 43, 43, and the yoke put into place and the spring 44 connected thereto by the cross-bar 50, which is put into the pair of notches 49, 49 on yoke 48, which will give the desired spring tension. The yoke 48 being pushed down, stretching spring 44 and bringing it into a state of tension, the entire assembly is complete and ready for use and the box cover may be replaced.

I claim:

1. Intersecting railway track parts, comprising a housing part adapted to be carried by the ties and comprising side walls and vertically arranged cross webs of less height than the side walls, and a separate wearing part carried by cross web portions of the housing part, and means for removably securing such parts together.

2. In an intersecting railway track parts, a supporting member of material, such as cast steel, comprising side plates and cross webs terminating below the upper edges of the side plates, a removable wearing portion inserted in said supporting member between the side plates and carried upon said cross-

webs, and means at the edges of the wearing portion for removably securing same to the said side plates. 65

3. In railway track members, such as switches, frogs and the like, a permanent housing adapted to be carried by cross-ties 70 or the like, having a recess in its upper surface with a flat horizontal bearing portion, a removable wearing member of high wear resisting properties having a flat horizontal undersurface and adapted to be received in 75 said recess, and wedge means for removably holding said members in such relative position with their flat bearing surfaces in firm contact, said housing comprising side bars and cross-connecting bars cast into an 80 integral structure.

4. The combination with a switch tongue of wedge means for supporting same to compensate for wear.

5. The combination with a switch tongue 85 of a stop for preventing upward movement thereof, and wedge means for holding the switch tongue up against the stop.

6. In combination a switch tongue, means for holding its heel against rising, a wedge 90 under the heel of the switch tongue for wedging same upwardly and spring means for resiliently forcing the wedge into wedging engagement with the under side of the switch tongue. 95

7. In combination a switch tongue pivoted to turn on its heel, means comprising a rearward extension of the switch tongue for holding the heel of the switch tongue down, a wedge under the tongue heel, and adjustable spring tension means for forcing the wedge into wedging engagement with the under side of the heel of the switch tongue. 100

8. In combination, switch rail members and a cross-connecting member formed integral with the switch rail members, said cross-connecting member having an integral stepped down portion, a switch tongue with its heel over such stepped down portion and a wedge between the said stepped down portion and the switch tongue heel. 105

9. In combination, switch rail members and a cross-connecting member formed integral with the switch rail members, said cross-connecting member having an integral stepped down portion, a switch tongue with its heel over such stepped down portion, a wedge between the said stepped down portion and the switch tongue heel, and spring means for forcing the wedge into wedging engagement with the under side of the heel of the switch tongue. 110

10. A switch tongue having an inclined under part, and a wedge member therebelow adapted to coact with said inclined portion and wedge same upwardly. 115

11. A switch tongue, means for holding the heel of the tongue down and wedging

means comprising relatively short substantially flat steps for holding the heel of said tongue upward.

12. A switch tongue, an extension from the lower part thereof, stop means engaging said extension for preventing same from rising, wedging means under the heel of the switch comprising a plurality of rela-

tively short stepped wedge portions, and spring means for holding said wedging means into wedging engagement and preventing looseness of the switch tongue due to wear.

In testimony whereof, I have signed my name hereto.

MAURICE C. GARLICK.
